(57) **CLAIM**

The ornamental design for a post arrangement for game, as
shown and described.

DESCRIPTION

The file of this patent contains at least one drawing/photograph executed in color. The copies of this patent with color drawing(s)/photograph(s) will be provided by the Office upon request and payment of the necessary fee.

FIG. 1 is a top, front right perspective view of a post arrangement for game showing our new design;

FIG. 2 is a front elevational view thereof;

FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a perspective view of a second embodiment of a post arrangement for game;
FIG. 9 is a front elevational view of FIG. 8;
FIG. 10 is a rear elevational of FIG. 8;
FIG. 11 is a left side elevational view of FIG. 8;
FIG. 12 is a right side elevational view of FIG. 8;
FIG. 13 is a top plan view of FIG. 8;
FIG. 14 is a bottom plan view of FIG. 8;
FIG. 15 is a perspective view of a third embodiment of a post arrangement for game;
FIG. 16 is a front elevational view of FIG. 15;
FIG. 17 is a rear elevational of FIG. 15;
FIG. 18 is a left side elevational view of FIG. 15;
FIG. 19 is a right side elevational view of FIG. 15;
FIG. 20 is a top plan view of FIG. 15;
FIG. 21 is a bottom plan view of FIG. 15;
FIG. 22 is a perspective view of a fourth embodiment of a post arrangement for game;
FIG. 23 is a front elevational view of FIG. 22;
FIG. 24 is a rear elevational of FIG. 22;
FIG. 25 is a left side elevational view of FIG. 22;
FIG. 26 is a right side elevational view of FIG. 22;
FIG. 27 is a top plan view of FIG. 22;
FIG. 28 is a bottom plan view of FIG. 22;
FIG. 29 is a perspective view of a fifth embodiment of a post arrangement for game;
FIG. 30 is a front elevational view of FIG. 29;
FIG. 31 is a rear elevational of FIG. 29;
FIG. 32 is a left side elevational view of FIG. 29;
FIG. 33 is a right side elevational view of FIG. 29;
FIG. 34 is a top plan view of FIG. 29;
FIG. 35 is a bottom plan view of FIG. 29;
FIG. 36 is a perspective view of a sixth embodiment of a post arrangement for game;
FIG. 37 is a front elevational view of FIG. 36;
FIG. 38 is a rear elevational of FIG. 36;
FIG. 39 is a left side elevational view of FIG. 36;
FIG. 40 is a right side elevational view of FIG. 36;
FIG. 41 is a top plan view of FIG. 36; and,
FIG. 42 is a bottom plan view of FIG. 36.
The broken lines indicate the unclaimed portions and form no part of the claimed design.
